UNITED STATES PATENT OFFICE.

PAUL A. MEEHAN AND HARRY M. ROBERTSON, OF CLEVELAND, OHIO, ASSIGNEES TO
AMERICAN DRESSLER TUNNEL KILNS, INC., OF CLEVELAND, OHIO, A CORPORA-
TION OF NEW YORK.

TUNNEL KILN.

Application filed June 30, 1922, Serial No. 571,976. Renewed September 30, 1925.

Our present invention relates to continuous tunnel kilns for use in the heat treatment of material which needs to be exposed for a considerable period of time to high temperatures and needs to be stirred continuously or at frequent intervals during such exposure and our present invention was devised with the general object of providing simple and effective means for suitably stirring the material during its passage through the kiln.

The various features of novelty which characterize our invention are pointed out with particularity in the claims annexed to and forming a part of this specification.

For a better understanding of our invention, however, its advantages and specific objects attained with its use, reference should be had to the accompanying drawings in which we have illustrated and described preferred embodiments of our invention.

Of the drawings:

Fig. 1 is a plan of a kiln equipped with our invention;

Fig. 2 is a sectional elevation on the line 2—2 of Fig. 1;

Fig. 3 is a transverse section on the line 3—3 of Fig. 1;

Fig. 4 is a view taken similarly to Fig. 3 illustrating a modified form of stirrer;

Fig. 5 is a view taken similarly to Fig. 3 illustrating another form of stirring mechanism;

Fig. 6 is a section on the line 6—6 of Fig. 5; and

Fig. 7 is a partial section on the line 7—7 of Fig. 6.

In the drawings, and referring first to the construction shown in Figs. 1, 2, and 3, we have illustrated the use of our invention in a continuous tunnel kiln of the well known Dressler type in which the kiln chamber is heated by combustion chambers B longitudinally disposed in the kiln chamber at opposite sides of the goods pathway and extending in the particular kiln shown practically the entire length of the kiln.

Adjacent one end, each combustion chamber is provided with a distributed set of burner inlets C, and at their opposite ends the combustion chambers are provided with outlets D connected by the conduit D' to a suitable draft creating device such as the

stack E. The cars G which run through the kiln on the track rails F comprise metallic underframes on which the car wheels are mounted, and refractory bodies which may be of the usual form. Mounted above the refractory body proper of each car is a work holding platform H which is made of suitable refractory material, and is formed at its upper side with a trough shaped cavity H'. This cavity extends longitudinally of the car, and the cavities of the different cars in the kiln unite to form a continuous trough-like receptacle for the material treated which extends the full length of the kiln. To facilitate the heating of the material open ended transverse channels G' are advantageously formed in the car structure between the refractory body portion proper and the material receiving platform. The usual cooling pipes F', or the like may be employed to cool the metallic under-portions of the cars.

Our invention is capable of use in various ways and for treating various forms of material. The particular construction illustrated in Figs. 1, 2 and 3 was primarily devised, and is especially adapted for use in preparing a base material for the manufacture of bicarbonate of soda, by heating a mixture of lime, soda ash and chrome iron ore to a temperature of approximately 2200° F. and subjecting the material to an oxidizing action at this temperature.

In the preferred contemplated mode of operation, the cars G are inserted into the kiln, one at a time, in the usual manner from a transfer car or tube J and preferably the cars are quite hot when inserted. The cars G are empty when inserted, and each car after being in the kiln for a period corresponding to its movement of one or two car lengths and correspondingly heated, is charged through a charging funnel L mounted in the roof of the kiln. Each car after passing through the kiln is received by a car transfer K, and is then returned to the transfer table J along the return track I, and is reinserted in the kiln. The treated material is raked off each car outside of the kiln at any suitable point along the path traversed by the cars. Preferably the period between the removal of a car from the kiln at the exit end of the latter, and its reinser-

tion into the entrance end of the kiln is made quite short so that the car will not cool off much while out of the kiln.

For the effective heat treatment and oxidation of the material it is unnecessary to stir the latter as it passes through the kiln. This stirring of the material is accomplished in the apparatus shown in Figs. 1, 2, and 3 by means of a plurality of sets of stationary plows M distributed along the length of the kiln. These plows M are formed of metal and as shown in Figs. 1, 2, and 3, the plows M of each set are secured to a corresponding metallic yoke member N, the legs of which extend through the roof of the kiln. Each yoke member N is hollow to receive a cooling fluid such as water. As indicated by the arrows in Fig. 3, the hollow interiors of the various yokes N are connected to a water circulating piping system comprising pipes O running longitudinally of the kiln. The plows M extend down into the material nearly to the bottom of the trough H', and each set of plows extend across the width of the trough, so that as the cars move slowly past the plows M, the material is constantly being agitated, and has fresh surfaces exposed to the kiln atmosphere. The cooling of the plow supporting yokes N, and thereby of the plows M by the circulation of water through the yokes N, enables the plows and supports to stand up under the severe condition of operation to which they are subjected.

It will be apparent, of course, that many modifications may be made in the form of the stirring provisions employed, and in Fig. 4 we have illustrated a modification in which each plow MA is made hollow, and is secured to the lower end of a tubular post M¹⁰ projecting down through the roof of the kiln. Axially disposed within each tubular post M¹⁰ is a circulation pipe M¹⁵ of smaller external diameter than the bore of the post. As shown clearly in Fig. 4, the posts M¹⁰ and pipes M¹⁵ for each set of plows MA, are connected between cooling water supply and discharge pipes O¹⁰ and O¹¹, so that the cooling water flows down through each pipe M¹⁵ into the cavity of the corresponding plow MA, and then flows up through the space between the pipe M¹⁵ and the wall of the hollow post M¹⁰.

To avoid the necessity of water cooling the stirrers we may insert the stirrers into the kiln, and remove them therefrom at sufficiently frequent intervals, and for sufficiently short periods of time to thereby properly stir the material without heating the stirrers up to a destructive temperature. One arrangement for this purpose is shown in Figs. 5, 6 and 7, wherein the kiln AA shown and the cars employed may be similar to those shown in Figs. 1, 2 and 3 except that openings A' are formed in the roof of

the kiln at frequent intervals along the length of the latter. These openings permit the insertion and removal of stirrers R. When the latter are out of the kiln chamber the openings A' are closed as by means of the doors Q. Each stirrer R as shown in Figs. 5, 6, and 7 is in the form of a rotary head carried by a vertically disposed stem S which is longitudinally and rotatably movable. As shown each stem S is externally corrugated to provide circular gear teeth in mesh with gear wheels W and W'. The gear wheels W are mounted on a driving shaft X which extends lengthwise of the kiln and may be rotated first in one direction and then in the other by a suitable motor or other driving device (not shown). The gears W' are idlers opposed to the gears W, and forming roller guides for the stems S. Each stem S is tubular and is splined on a corresponding vertically disposed driving shaft T. Each shaft T is provided at its upper end with a bevel gear T' in mesh with a corresponding bevel gear carried by a driving shaft U running longitudinally of the kiln and rotated by a suitable motor or other driving device (not shown). Each stirrer R is mounted in a corresponding supporting frame r, shown as a metallic yoke supported on beams r' carried by the kiln buckstays.

In the intended operation of the form of our invention shown in Figs. 5, 6, and 7, the doors Q are opened at intervals to permit the insertion into the kiln chambers of stirrers R which are lowered into place by rotating the gears W in a counter clockwise direction. The shaft U may rotate continuously and in any event is rotated as the stirrers are moved down into contact with the material and until the stirrers are again retracted from the kiln. Each stirrer R is of sufficient width to stir the material all the way across the width of the trough shaped receptacle formed by the cavities H' of the various cars G. When the stirrers are inserted in the kiln, the doors Q are closed, notches Q' being formed in the edges of these doors to receive the stem portions S of the stirrers. After a brief stirring period not sufficiently prolonged to heat the stirrers R to a destructive temperature, the doors Q are opened, the gears W are rotated in a clockwise direction to retract the stirrers to the position shown in Fig. 5, after which the doors Q are again closed. The stirrers are left out of the kiln chamber long enough for them to cool off as much as may be necessary before the stirring operation is repeated.

While in accordance with the provisions of the statutes we have illustrated and described the best forms of our invention now known to us, it will be apparent to those skilled in the art that changes may be made in the form of the apparatus disclosed with-

out departing from the spirit of our invention as set forth in the appended claims and that certain features of our invention may sometimes be used to advantage without a corresponding use of other features.

Having now described our invention, what we claim as new and desire to secure by Letters Patent, is:

1. In a continuous tunnel kiln the combination with the kiln chamber and track rails therein, of means for transporting material through the kiln chamber comprising a train of cars each comprising a metallic underframe with track engaging wheels mounted therein and a refractory superstructure formed with a trough-like cavity in its upper face which extends longitudinally of the car and unites with the corresponding cavities of the other cars to form a continuous trough extending the length of the train.
2. In a continuous tunnel kiln the combination with the kiln chamber and track rails therein, of means for transporting material through the kiln chamber comprising a train of cars each comprising a metallic underframe with track engaging wheels mounted therein and a refractory superstructure formed with a trough-like cavity in its upper face which extends longitudinally of the car and unites with the corresponding cavities of the other cars to form a continuous trough extending the length of the train and stirrers extending downward from the roof of the kiln into said trough.
3. In a continuous tunnel kiln the combination with the kiln chamber and track rails therein, of means for transporting material through the kiln chamber comprising a train of cars each comprising a metallic underframe with track engaging wheels mounted therein and a refractory superstructure formed with a trough-like cavity in its upper face which extends longitudinally of the car and unites with the corresponding cavities of the other cars to form a continuous trough extending the length of the train and fluid cooled stirrers extending down-

ward from the roof of the kiln into said trough.

4. In a continuous tunnel kiln, the combination with the kiln chamber, of a traveling platform for transporting material through said chamber and fluid cooled devices mounted in the kiln chamber and engaging and agitating the material on the platform as the latter is advanced.

5. In a continuous tunnel kiln, the combination with the kiln chamber, of a traveling platform for transporting material through said chamber, of stirrers engaging said material and agitating the latter as the platform is advanced and hollow supports for said stirrers extending through the wall of the kiln chamber and externally connected into a cooling fluid circulation system.

6. In a continuous tunnel kiln, the combination with the kiln chamber, of a traveling support for transporting material through the kiln chamber, of a series of rotatable stirrers movable into and out of the kiln chamber and adapted when in the latter to engage and stir the material on said support.

7. In a continuous tunnel kiln, the combination with a kiln chamber formed with a series of apertures in its roof, of a traveling support for transporting material through said chamber and a series of material stirrers movable into and out of said chamber through said roof and means for rotating said stirrers.

8. In a continuous tunnel kiln, the combination with a kiln chamber formed with a series of apertures in its roof, of a traveling support for transporting material through said chamber and a series of material stirrers movable into and out of said chamber through said roof and a common means for rotating said stirrers as they are being inserted and while in said chamber.

Signed at Cleveland in the county of Cuyahoga and State of Ohio this twenty-seventh day of June A. D. 1922.

PAUL A. MEEHAN.
